COLLAR-STAY

Harold T. Krick, Hazleton, Pa.

Application September 2, 1933, Serial No. 687,926

2 Claims. (Cl. 2—132)

The object of my invention has been to provide a collar-stay having the following advantages; that of imparting to the points of soft or semi-soft collars sufficient stiffness to keep them extended, while yet having reasonable resilience; of causing the said points normally to lie close to the shirt and reasonably close to each other, and of lying close to the collar band, and to perform these functions without causing distortions of the collar, or revealing the presence of the stays; and to such ends my invention consists in the collar-stay hereinafter specified.

In the accompanying drawing, Fig. 1 is a front elevation of a sport shirt having a soft collar attached thereto, each point of which collar is provided with one of my collar-stays, a necktie being shown in proper relation to said collar and collar-stays.

Figs. 2 and 3 are respectively a front elevation and an edge view of one of the collar stays shown in Fig. 1.

Figs. 4 and 5 are respectively a front and an edge view of another form of my collar-stay, and

Fig. 6 is a view showing the metal clips which, in Figs. 4 and 5, are attached to the collar stay.

As shown in Figs. 2 and 3, my collar stay is formed by being cut out of a sheet of stiff but flexible material, preferably of celluloid. It comprises a straight shank 1, which is adapted to be secured to the front edge of one of the points of the collar, as by being inserted in a pocket 2, formed on the underside of such edge for that purpose. I have tapered the shank 1 because that renders it slower and more flexible than its body portion. From the shank 1, a section 3 extends upwardly, and preferably is also offset away from said front edge of the collar point, so as to leave room for the knot of the tie between the two stays. The said section 3 curves over at the point 4 and merges into a downwardly extending anchor 5 which is adapted to be engaged between the band 6 of the necktie and the collar band. The curve 4 engages the underside of the crease of the collar and thus maintains the stay in the aforesaid pocket.

In putting the stays in place, the wearer puts a shank of a stay into the pockets of each of the points of his collar and puts on the shirt as usual. The tie then is knotted in place, after which, using his right hand to pull the knot of the tie slightly downward, he reaches under the left collar point with the forefinger and thumb of the left hand, places the tie in the slot 7,

Thus the anchor is placed between the tie band and the collar band. Reversing the functions of his hands, he then places the anchor of the other stay behind the tie band and adjusts the knot in the open space between the extensions 3 of the two stays.

The parts of the said stay are preferably all in the same plane, when not being used. The anchor 5 is pressed against the collar band by the pressure of the tie band; it is preferably not fitted into a pocket and is free to slide along both the tie and the collar. For this purpose, the slot 7 between the extension 3 and the anchor 5 is relatively large. The point where the curve 4 contacts with the collar crease, being further away from the center line of the shirt than the shank 1, tends not only to keep the shank of the stay in its pocket, but it tends also to swing the shank toward the other point of the collar, so that the two points are prevented from unduly separating.

Any tendency to vertically upward movement of the collar point is resisted by the stoppage of the curved section 4 against the collar crease. Any force applied directly upwardly, to the point 25 of the collar, would tend to swing the lower ends of the stays toward each other. The pressure of the tie band against the anchor 5 tends to hold the points of the stay, and therefore the points of the collar, against the shirt.

The tip 5a of the anchor is preferably so located that it extends substantially nearer to the centerline of the shirt than does the curved point 4 which engages the crease of the collar. This causes the pressure of the tie band on the 35 said anchor tip to press the edge of the collar point inward in opposition to the tie knot, instead of outward away from the wearer (3 is wide and stiff for the same reason). It also tends to prevent the knot from causing the side 40 edge 5b of the anchor, which is farthest from the centerline of the shirt, from bearing against the neck; and thus it tends to cause the rear face of the anchor to lie flat against the neck.

By making my stays so that all parts are in a 45 plane, as I prefer, the stays are interchangeable and will work equally well in either collar point; if they take a "set" as celluloid is likely to do from warmth, the distortion can be removed by interchanging the two stays. The parts of my 50 stays extend for so short a distance horizontally around the circumference of the neck that they do not need to be curved to the neck in order to avoid distorting the collar. Furthermore, the anchor 5 is preferably made narrow, so that it 55

will be comparatively flexible. Under these conditions, the wearer does not feel any discomfort from the use of the stay.

Various changes can be made in the above 5 illustrative embodiment of my invention. For instance: In order to enable my collar stays to be used on collars which have no pocket for the shank, I may provide them, as shown in Figs. 4, 5 and 6, with metal clips 8 and 9, carrying pins 8a and 9a each projected in opposite directions, the clips being bent about the celluloid shank, and clamped thereto.

By flexing the shanks of the collar stays, the 10 pins 8a and 9a may be brought nearer to each other and their points engaged in the material of the collar point, whereupon releasing the said shank will cause the pins to penetrate the said material in opposite directions and fasten the stay in place. Again, the anchor may be placed 15 on the opposite sides of the shanks from those shown, or they may be placed directly behind the extension 3. Such changes, however, would have the disadvantage of interfering with the knot of the tie and/or increasing the thickness 20 of the stay within the collar which latter would tend to cause distortion of the surface of the collar. The curve or offset to allow the space for the knot may be omitted, but I prefer to have it present.

I desire to emphasize particularly the importance 25 of the fact that neither the tie band nor the collar band is fastened to the stay. The freedom of movement of the stay between the tie band and the collar band permits automatic 30 adjustment when made necessary by a change in the wearer's bodily position. It also permits

accommodation to a change of relation of the collar points and the collar band. My form of anchor, also, will fit tie bands of varying widths. The comparatively short radius of the curve of the rounded portion 4 permits movement of the 5 collar stay relative to the crease of the collar without causing distortion due to angular movement of the stay in its own plane.

I have found by experience that my stay works 10 reasonably well if the anchor is not used, but I prefer to use the anchor.

While I have described my stay as made of celluloid, which is the best material for that purpose known to me there are many other materials which would serve the purpose.

What I claim is:

1. A collar-stay comprising a shank adapted to be attached to a collar point, said stay having an offset hooked portion adapted to engage the upper edge only of the tie band, and to lie between said tie band and the collar band, said offset being sufficient to accommodate the knot of the necktie, said hooked portion having a curved upper edge, all parts of the said collar-stay when not engaged to said necktie band 25 normally lying substantially in the same plane.

2. A collar-stay comprising a shank adapted to be attached to a collar point, said stay having a hooked portion adapted to engage the upper edge of a tie band and to lie between the said tie band and the collar band, all parts of said collar stay, when not engaged to said necktie band, normally lying substantially in the same plane.

HAROLD T. KRICK.
